UNITED STATES PATENT OFFICE.

HARRY E. HEATH, OF WINDSOR, CONNECTICUT, ASSIGNOR TO GENERAL ELECTRIC COMPANY, A CORPORATION OF NEW YORK.

MAGNETIC SEPARATOR.

No. 805,289.

Specification of Letters Patent.

Patented Nov. 21, 1905.

Application filed September 17, 1903. Serial No. 173,507.

To all whom it may concern:

Be it known that I, HARRY E. HEATH, a citizen of the United States, residing at Windsor, county of Hartford, State of Connecticut, have 5 invented certain new and useful Improvements in Magnetic Separators, of which the following is a specification.

This invention relates to machines for separating magnetic material from ores or scrap; 10 and it consists in a plurality of traveling pole-pieces arranged to pass in proximity to a stationary energizing-conductor at some point in their movement, whereby they will become magnetized and will attract the substance to 15 be separated from a mass of material moved transversely to the line of travel of said pole-pieces.

In the accompanying drawings, Figure 1 is 20 an end elevation of a machine embodying my invention, and Fig. 2 is a side elevation of the same.

The material to be treated, which may be crushed ore, shop-sweepings, scrap, or the like, is fed from a hopper 1 to a suitable conveyer, preferably a level endless carrier-belt 2, moving continuously in one direction. At one or more points above the conveyer is a stationary conductor, preferably a single copper bar 3, through which an electric current 25 flows from some suitable source, such as the generator 4. The conductor lies transverse to the conveyer 2, and above it is arranged an endless series of soft-iron pole-pieces 5, preferably in the form of an endless belt running 30 over suitable supporting and driving pulleys 6, by means of which said pole-pieces are caused to travel across the carrier-belt 2 in proximity to the conductor 3. The pole-pieces are preferably bifurcated, so as to straddle 35 said conductor and depend below it. The current in said conductor magnetizes the pole-pieces, so that as they pass across the carrier-belt they pick up the magnetic particles from 40 the material on said belt and carry it to one side. The point where the pole-pieces move up and away from the conductor is beyond 45 the edge of the carrier-belt, and they prefer-

ably pass so close to the conductor that the magnetic material 7 is stripped off by the conductor and drops into a suitable receptacle. 50 The particles not scraped off in this manner fall off of themselves when the pole-pieces pass out of the field of the conductor and lose their magnetism. The tailings 8 are dumped off the end of the carrier-belt. 55

In accordance with the patent statutes, I have described the principle of operation of my invention, together with the apparatus which I now consider to represent the best embodiment thereof; but I desire to have it 60 understood that the apparatus shown is only illustrative and that the invention can be carried out by other means.

What I claim as new, and desire to secure by Letters Patent of the United States, is— 65

1. In a magnetic separator, the combination with a stationary conductor, of a plurality of pole-pieces traveling longitudinally thereof and in proximity thereto, and means for conveying the material to be treated beneath said 70 pole-pieces.

2. In a magnetic separator, the combination with a stationary conductor, of an endless series of soft-iron pole-pieces, and means for moving them in proximity to said conductor and to a 75 conveyer.

3. In a magnetic separator, the combination with a stationary conductor, of a plurality of bifurcated pole-pieces straddling said conductor, and means for moving said pole-pieces 80 along said conductor and above a conveyer.

4. In a magnetic separator, the combination with a carrier-belt, of a conductor transverse to said belt, a plurality of pole-pieces, and means for moving same in proximity to said conductor across said belt and up close to and away from the conductor at a point beyond the edge of the belt. 85

In witness whereof I have hereunto set my hand this 14th day of September, 1903.

HARRY E. HEATH.
